UNITED STATES PATENT OFFICE.

H. L. HOPKINS, OF SAN FRANCISCO, CALIFORNIA.

IMPROVED AMALGAMATOR.

Specification forming part of Letters Patent No. 44,122, dated September 27, 1864.

To all whom it may concern:

Be it known that I, H. L. HOPKINS, of San Francisco, in the county of San Francisco and State of California, have invented a new and Improved Amalgamator; and I do hereby declare that the following is a full, clear, and exact description thereof, which will enable others skilled in the art to make and use the same, reference being had to the accompanying drawings, forming part of this specification, in which—

Figure 1 represents a longitudinal vertical section of a portion of my invention, taken in the line *xx*, Fig. 4; Fig. 2, a transverse vertical section of the same, taken in the line *yy*, Fig. 4; Fig. 3, an end view of the same; Fig. 4, a plan or top view of the same.

Similar letters of reference indicate like parts.

This invention consists in the employment or use of a cylindrical case provided with dies, and having a rotary oblique muller placed within it and provided with shoes, all being constructed and arranged in such a manner that all particles of the quartz or rock will be brought in contact with the quicksilver and the metal contained in the quartz or rock thoroughly amalgamated, and without cutting up or grinding the quicksilver so that the latter will be liable to float off with the scum on the water, as is now the case to a great extent, and which involves a considerable loss in quicksilver.

A represents a cylinder, which is supported in a horizontal position on legs *a*. The lower part of the interior of this cylinder is provided with dies or plates *b*, between which narrow spaces *c* are allowed to form cutting or grinding surfaces and recesses to catch and hold the quicksilver. (See more particularly Fig. 2.)

B represents a muller, which may be described as being an oblique section of a cylinder which forms an ellipse. This muller is placed obliquely on a shaft, *C*, and extends the whole length of the interior of the cylinder *A*.

The breadth of the face of the muller may be greater or less, as may be desired, and it is covered with shoes *d*, the latter being bolted to the former. The shoes *d*, as well as the dies or plates *b*, may be of white or hard iron. The shaft *C* is fitted in boxes *D*, which are allowed a certain degree of vertical play in the sides of the cylinder *A*, each box having a spiral spring, *E*, bearing upon it, in order to keep the muller pressed in close contact with the dies or plates *b*. This pressure, however, may be regulated by means of gages *E E* at each end of cylinder *A*, said gages being simply screws fitted in nuts *e*. (See Fig. 3.)

By constructing the muller in the manner as described a diagonal or oblique movement of the face of the muller over the dies or plates is obtained, which causes every particle of the rock or quartz to be brought in contact with the quicksilver which lies in the spaces *c* between the dies or plates *b*, and a thorough amalgamation of the metal is the result, while the quicksilver is not liable to be ground up and carried off with the scum which rises and floats on the pulp in the ordinary machines, and is the occasion of a great loss in quicksilver.

I claim as new and desire to secure by Letters Patent—

1. The muller *B*, formed of an oblique section of a cylinder, or, in other words, formed of an ellipse, placed obliquely on a shaft, *C*, with its periphery composed of a portion of a cylinder which is concentric with said shaft *C*, in combination with the cylindrical case *A*, all arranged substantially as and for the purpose set forth.

2. The plates or dies *b*, with the spaces *c* between them in the cylindrical case *A*, and the shoes *d* on the muller *B*, when said parts are applied to or used in combination with the case and muller, for the purpose specified.

H. L. HOPKINS.
